ELECTRIC FUSE

Henry Jaedike, Brooklyn, N. Y.

Application February 7, 1939, Serial No. 255,024

6 Claims. (Cl. 200—130)

This invention relates generally to fuses which are employed in electric circuits for imposing a predetermined limit on the load or current and pertains more particularly to improvements in electric fuses of the type which are known as "plug" or "cartridge" fuses.

The invention broadly comprehends an improved electric fuse which embodies relatively few and simple parts, more compactly arranged and of lighter weight and capable of more economical production than those heretofore produced.

More specifically the invention resides in an improved electric fuse in which the parts thereof are stamped or otherwise fashioned from sheet material thereby avoiding the necessity of molding, casting, spinning or other relatively expensive operations and wherein the parts are assembled in laminated form by means of rivets to provide a closely confined compact structure possessing a high factor of safety and stability.

With the above and other objects in view, the invention is set forth in greater detail in the following specification and illustrated in the accompanying drawing, in which:

Fig. 1 is a front view of a plug type fuse constructed in accordance with the invention and illustrating the same actively positioned in a socket.

Fig. 2 is a side edge view thereof.

Fig. 3 is a sectional view therethrough taken approximately on the line 3—3 of Fig. 2.

Fig. 4 is a bottom plan view thereof.

Fig. 5 is a perspective view of a modified form of the invention illustrating a cartridge type fuse.

Fig. 6 is a sectional view therethrough.

Referring to the drawing by characters of reference and particularly to the form of the invention illustrated in Figs. 1 to 4 inclusive, 40 A designates generally a plug type fuse and B a socket for receiving the same, which socket includes a threaded conducting rim 10 constituting one terminal of the fuse socket and a centrally disposed contact 11 insulated therefrom and serving as the other terminal of the fuse socket.

The fuse A includes a fusible element 15 which is fashioned from sheet material and of substantially U-shaped configuration providing a pair 50 of legs 16 and 17 joined by a bight portion 18. A pair of side plates 19 and 20 which are formed of flat sheets of insulation material are arranged on opposite sides of the fusible element 15 so as to dispose the fusible element therebetween and 55 wholly within the confines of the side plates so

that the fusible element is spaced from and within the marginal edges thereof.

Either one or both of the side plates are provided with window openings 21, in the present instance both plates being provided with window 5 openings disposed in alignment with each other so as to display therethrough the bight portion 18 of the fusible element 15. The side plates 19 and 20 are secured together with the fusible element 15 interposed therebetween by means of 10 rivets 22, one of which passes through the leg 16.

A contact foot 23 of conducting material is also interposed between the enlarged free end portion 24 of the leg 17 and one of the side plates and is secured in place by means of a rivet 25 passing through both of the side plates, the enlarged free end portion 24 of the fusible element and the contact foot 23, which latter protrudes beyond the end edges of the cover plates and is formed with an angularly disposed terminal 26. 20 A strip of conducting material 27 is arranged transversely and exteriorly of one of the side plates and is secured thereto by opposite rivets 22, one of which rivets extends through the leg 16 of the fusible element 15. 25

The strip 27 is provided with angularly disposed opposite ends 28 having enlarged concavo-convex finger pieces 29 defining at the opposite side edges of the fuse structure resilient means for cooperative engagement within the threaded conducting rim 10 at diametrically opposite sides thereof to frictionally retain the fuse A within the socket B against accidental or unintentional displacement, while permitting of the forceable removal thereof. 30

In order to assist in the retention of the fuse plug within the socket B, the finger pieces are formed with outwardly protruding teats 30 which more effectually engage the threads of the conducting rim of the socket. It will be observed 40 that the strip 27 together with its integral angularly disposed portions and finger pieces 29 are also formed of sheet material as is the contact foot 23.

In practice, the fuse will preferably include, as 45 illustrated, a pair of transparent panels of insulation sheet material 31 and 32 which are respectively interposed between the opposite sides of the fusible element 15 and the side plates 19 and 20 in the region of the window openings 50 21. This exposes the bight portion 18 of the fusible element to view, while covering and protecting the same.

As illustrated, the corners of the transparent panels 31 and 32 are cut away or notched as at 55

33 to engage with the rivets 22 so as to retain the panels in place between the side plates 19 and 20. The fuse may also be provided with a shield piece 34 which is made of sheet insulation material, slotted as at 35 and frictionally fitted over the fuse body and engaging with the transverse strip 27 so as to protect the fingers when the fuse is grasped by the upper portion thereof to effect the insertion of the lower end within 10 the socket B or the removal of the same therefrom.

In use it will be apparent that when the lower end of the fuse plug is inserted within the threaded conductor rim 10 of the socket B, the terminal 15 26 of the contact foot is brought into engagement with the center contact 11 of the socket, while the spring finger pieces frictionally retain the fuse plug in place and at the same time serve to effect electric contact with the conducting 20 rim so that the current flows from the central contact 11 through the contact foot 23, the leg 17 of the fusible element 15, thence through the bight 18, the leg 16 thereof, the rivet 22, the strip 27 and the conducting rim 10 of the socket. The 25 intermediate portion of the bight 18 is provided with oppositely disposed notches which, in event of an overload in the circuit, will cause fusing at this, the weakest part of the fusible element, where the "blowing" of the fuse may be readily 30 observed through the window openings and transparent panels.

In the modified form of the invention illustrated in Figs. 5 and 6 of the drawing, the fuse is of the character ordinarily known as the cartridge type and is adapted to be used in conjunction with a cartridge type fuse socket. In this form of the invention, the side plates 35 and 36 are of substantially T-shaped formation and are constructed of flat sheets of insulation material with the upwardly protruding stem portions 37 formed with aligned window openings 38. In this instance, the fusible element 39 is of substantially U-shaped formation and interposed between the side plates with the bight portion 40 thereof extending across the window openings 38 and with the depending leg portions 41 and 42 thereof formed respectively with outwardly directed feet 43 and 44.

Mating pairs of contact elements 45 and 46 are located on opposite sides of the lower end portions of the side plates and are attached to the fuse body by means of rivets 47 and 48 which extend through the contact elements, the side plates and the feet 43 and 44 of the fuse element, 55 the rivets serving in addition to means for holding the parts in assembled relation, as means for electrically connecting the contacts to the opposite ends of the fuse element. The contact elements 45 and 46 are provided with resilient substantially semi-cylindrical extremities 49 and 50 which are adapted to be received within the clip-like terminals of the usual cartridge type fuse socket.

Preferably transparent panels 51 of insulation sheet material are arranged on opposite sides of the fusible element and interposed between the same and the opposite side plates so as to cover and protect the bight portion 40 of the fuse element which is displayed through the window openings 38.

What is claimed is:

1. An electric fuse plug including a flat elongated laminated body structure comprising a flat metallic fusible strip, a pair of flat non-conductor side plates disposed on opposite sides of

fusible strip in covering relation therewith, resilient sheet metal contact members for engagement respectively with the opposite terminals of a plug type socket, one of said contact members having resilient wing portions located respectively at the opposite side edges of the body and the other having a resilient wing portion located at one end edge of the body and the wing portions of one contact member being disposed in parallel planes perpendicular to the plane of the body 10 with the wing portion of the other contact member disposed in a plane perpendicular to the wings of the said first contact member and perpendicular to the body, and a common means for securing said contact members respectively to the 15 opposite ends of the fusible strip and for holding the side plates in covering relation with the fusible strip.

2. In an electric fuse plug, a flat elongated laminated body structure including a flat metallic fusible strip, a pair of flat non-conductor side plates disposed on opposite sides of the fusible strip in covering relation therewith, sheet metal contact members for engagement with the opposite terminals of an electric socket, one of 20 said contact members including offset resilient portions at the opposite side edges of the body structure disposed in a plane perpendicular to the plane thereof and adapted to engage with the threads of the conducting rim of a plug type 25 socket for releasably retaining the plug in the socket, and a common means for securing said contact members respectively to the opposite ends of the fusible strip and for holding the side plates 30 in covering relation with the fusible strip. 35

3. In an electric fuse plug, a flat elongated body structure including a flat metallic fusible strip, a pair of flat non-conductor side plates disposed on opposite sides of the fusible strip in covering relation therewith, sheet metal contact 40 members for engagement with the opposite terminals of an electric socket, one of said contact members including a metallic strip disposed transversely upon one of said side plates and having offset resilient end portions at the opposite side edges of the body structure disposed in parallel planes perpendicular to the plane of the body structure and adapted to engage within the conducting rim of a fuse socket at diametrically opposite points thereof for releasably retaining 50 the plug in the socket, the other contact member being disposed at the end edge of the body structure and having an angulated terminal disposed in a plane perpendicular to the plane of the body structure and to the planes of the end portions 55 of the other contact member, and a common means for securing said contact members respectively to the opposite ends of the fusible strip and for holding the side plates in covering relation to the fusible strip. 60

4. An electric fuse including a laminated body consisting of outer plates of flat sheet insulation material at least one of which plates is provided with a window opening, a fusible element of flat sheet material interposed therebetween and having a portion thereof displayed through the window opening, a transparent panel of insulation material arranged between said fuse element and the plate in the region of the window opening to cover the portion of the fuse element displayed therethrough, spaced sheet metal contact elements disposed exteriorly of the body and each having angulated terminal portions disposed in planes perpendicular to each other and perpendicular to the plane of the body for engaging 70 75

with opposite terminals of a fuse socket, and rivets extending through said laminated body for securing the plates, the fusible element and the contact elements in assembled relation and for electrically connecting said contact elements with the fusible element.

5. An electric fuse including a laminated body consisting of outer plates of flat sheet insulation material at least one of which plates is provided 10 with a window opening, a fusible element of flat sheet material interposed therebetween and having a portion thereof displayed through the window opening, a transparent panel of insulation material having notched corners arranged between 15 said fuse element and the plate in the region of the window opening to cover the portion of the 10 fuse element displayed therethrough, spaced pairs of sheet metal contact elements disposed exteriorly of and on opposite sides of the body and having flat bases and mating semi-cylindrical resilient extremities each reversely curved 15 to dispose the free end thereof adjacent the free end of the base and which pairs of contact elements are adapted for engagement with opposite terminals of a cartridge type fuse socket, and rivets extending through said outer plates, the 20 opposite ends of the fusible element, and the bases of the contact elements for securing the same in assembled relation and for electrically connecting said contact elements with the fusible 25 element.

6. An electric fuse including a flat laminated body consisting of outer plates of flat sheet insulation material at least one of which plates is provided with a window opening, a fusible element of flat sheet material interposed therebetween and having a portion thereof displayed through the window opening, a transparent panel of insulation material arranged between said fuse element and the plate in the region of the window opening to cover the portion of the 10 fuse element displayed therethrough, spaced pairs of sheet metal contact elements disposed exteriorly of and on opposite sides of the body and having flat bases and mating semi-cylindrical resilient extremities each reversely curved 15 to dispose the free end thereof adjacent the free end of the base and which pairs of contact elements are adapted for engagement with opposite terminals of a cartridge type fuse socket, and rivets extending through said outer plates, the 20 opposite ends of the fusible element, and the bases of the contact elements for securing the same in assembled relation and for electrically connecting said contact elements with the fusible 25 element.
